UNITED STATES PATENT OFFICE.

GEORGE WASHINGTON CLAPP AND BARNEY F. LOW, OF GIBSONVILLE, NORTH CAROLINA, ASSIGNORS OF PART TO W. F. NEAL, R. C. DICK, W. M. CLAPP, AND D. E. CLAPP, OF SAME PLACE.

CHURN.

SPECIFICATION forming part of Letters Patent No. 415,357, dated November 19, 1889.

Application filed July 23, 1889. Serial No. 318,394. (No model.)

To all whom it may concern:

Be it known that we, GEORGE WASHINGTON CLAPP and BARNEY F. LOW, citizens of the United States, residing at Gibsonville, in the county of Guilford and State of North Carolina, have invented a new and useful Churn, of which the following is a specification.

This invention has relation to churn-motors of that class known as "rocking body," and in which a rocking-chair is employed as the motive agent; and the invention consists in certain features of construction and combination of parts, hereinafter referred to, and particularly pointed out in the claims.

Referring to the drawings, Figure 1 is a perspective of a churn and motor constructed in accordance with our invention. Fig. 2 is a transverse section of the churn detached; Fig. 3, a perspective of the churn-base; Fig. 4, of the connecting-levers.

Like numerals of reference indicate like parts in all the figures of the drawings.

1 represents an ordinary rocking-chair, and 2 the base, the rockers and base being connected by oppositely-located coiled springs 3, said rocker being of that class commonly termed "spring-rockers." The side pieces 4 of the base are connected by rungs 5, which 30 project beyond the base, and also connect a pair of rungs 6^a, passed through opposite churn-standards 6, by means of a sleeve 5^a and set-screw 4^a. Upon the standard is mounted the churn-body 7, provided at each 35 side with a rocker 8, operating upon the upper edge of its respective standard. Springs 9 connect each standard with a rocker, and thus the churn is maintained in position upon the standards.

42 To the outer face of the inner churn-standard is pivoted a lever 11 by means of a pivot-bolt 12, and to the rear end of the lever is pivoted, by means of a bolt 12^x, the lower end of a depending arm 13, the upper end of 45 which is secured to the side of a churn-body. A short lever 14 has its lower end connected by a bolt 15 to the opposite end of a main lever, and the upper end of said short lever is pivoted to the front corner of the seat of the 50 chair. Removable covers 17 are provided

upon the churn-body, said body being of the well-known rocking construction.

The operation of our invention will be readily apparent from the above description, in that through the rocking motion of the chair 55 said motion will be conveyed by the lever-connection described to the churn, but in an exaggerated movement by reason of the fact of the lever connecting the chair with the main lever being shorter than the rear lever, 60 which connects the main lever with the churn, and by reason of the further fact that said main lever is pivoted not at its center but near its forward end, so that a slight rocking of the chair will impart a comparatively violent rocking of the churn-body. By reason of the spring-connection described the momentum and sudden stoppage of the cream when coming in contact with the ends of the churn-body will not serve to jerk the chair, 70 but will act as a compensating spring.

Minor changes in the form, proportion, and arrangement of the parts may be made without departing from the spirit of this invention.

Having thus described our invention, what we claim is—

1. The combination, with a spring-rocker, of a base mounted at one side of the rocker, a rocking-body churn mounted on the base, 80 springs connecting the body and base, a lever pivoted to the side of the base, and opposite levers connecting one end of said lever with the churn and the opposite end with the chair, substantially as specified. 85

2. The combination, with a rocking-chair, of a base mounted at one side thereof, a churn provided with rockers mounted on the base and connected thereto by opposite springs, and a lever-connection with the chair and 90 body imparting a rocking motion from the former to the latter, substantially as specified.

3. The combination, with a spring-rocker the rounds of which are extended to one side, 95 of a pair of standards connected by the rounds, a churn-body provided with opposite rockers mounted on the standards, opposite springs connecting said standards and churn-body, a lever pivoted near one end to one of the 100

standards, a short connecting-lever pivoted to the shorter end of the first-mentioned lever and having its opposite end pivoted to the chair, and a depending arm pivotally connecting the longer end of the first-mentioned lever with one end of the churn, substantially as specified.

4. The combination, with the chair and its standards connected by rungs, of the churn and its standards connected by corresponding rungs, and sleeves connecting the two sets of

rungs and provided with a set-screw for binding the same in position, substantially as specified.

In testimony that we claim the foregoing as 15 our own we have hereto affixed our signatures in presence of two witnesses.

GEORGE WASHINGTON CLAPP.
BARNEY F. LOW.
